UNITED STATES PATENT OFFICE.

ELIZABETH SIMMONS, OF ST. LOUIS, MISSOURI.

DESIGN FOR A COMBINED LAMP AND BOOK END.

Application filed October 30, 1922. Serial No. 4,164. Term of patent 34 years.

To all whom it may concern:

Be it known that I, ELIZABETH SIMMONS, a citizen of the United States, residing at the city of St. Louis and State of Missouri, have invented a new, original, and ornamental Design for a Combined Lamp and Book End, of which the following is a specification, reference being had to the accompanying drawing, forming part thereof.

In the drawing the view is a side elevation showing my new design.

I claim:

The ornamental design for a combined lamp and book end, as shown.

ELIZABETH SIMMONS.
